Primary Examiner — Ian Simmons*Assistant Examiner* — Carissa C Fitts(74) *Attorney, Agent, or Firm* — McDonald Hopkins LLC(57) **CLAIM**

I claim the ornamental design for a lighting device, as shown and described.

DESCRIPTION

FIG. 1 is a front perspective view of the design;
 FIG. 2 is a rear perspective view of the design;
 FIG. 3 is a left side view of the design. The right side view of the design is a mirror image of the left side view;
 FIG. 4 is a front view of the design;
 FIG. 5 is a back view of the design;
 FIG. 6 is a top view of the design; and,
 FIG. 7 is a bottom view of the design.
 The broken line showing represents portions of the article not claimed and forms no part of the claimed design.
